UNITED STATES PATENT OFFICE

99,973

DESIGN FOR AN AUTOMOBILE HOOD STRUCTURE

Gordon Miller Buehrig, Auburn, Ind., assignor to
Auburn Automobile Company, Auburn, Ind., a
corporation of Indiana

Application May 11, 1936, Serial No. 62,601

Term of patent 7 years

To all whom it may concern:

Be it known that I, Gordon Miller Buehrig, a citizen of the United States, residing at Auburn, in the county of De Kalb and State of Indiana, have invented a new, original, and ornamental Design for an Automobile Hood Structure, of which the following is a specification, reference being had to the accompanying drawing, forming a part thereof.

Figures 1 and 2 of the drawing are side and front perspective views respectively of an automobile hood structure showing my new design.

The dominant feature of the present design resides in the substantially horizontal louvres which are arranged in superposed relation and around the front and sides of the hood structure.

I claim:

The ornamental design for an automobile hood structure substantially as shown and described.

Signed at Auburn, Indiana, this 1st day of May, 1936.

GORDON MILLER BUEHRIG.
